UNITED STATES PATENT OFFICE.

FRED J. PALMER, OF ELKHART, INDIANA.

REAMING OR SCRAPING TOOL.

Application filed August 4, 1921. Serial No. 489,895.

To all whom it may concern:

Be it known that I, FRED J. PALMER, a citizen of the United States, residing in the city of Elkhart, county of Elkhart, Indiana, have invented certain new and useful Improvements in a Reaming or Scraping Tool, of which the following is a specification.

This invention relates to devices for scraping or reaming valve seats and the face of the valve for internal combustion engines, or the like.

An object of my invention is to produce a valve and valve seat reaming or refacing tool for internal combustion engines, or the like, in which the cutting blade is adjustable and provided with a plurality of sets of cutting edges. Another object of the invention is the production of a tool of the character described and means in combination therewith, whereby either the valve seat in the engine or the face of the valve itself may be refaced while the valve is mounted in the device. Other objects of my invention are mentioned and described therein.

The preferred embodiment of my invention is illustrated in the accompanying drawings in which Figure 1 is a section taken through a fragment of an internal combustion engine cylinder showing my invention applied thereto for refacing the engine cylinder valve seat; Fig. 2 is a top plan view of my invention including a ratchet wrench and frame or carrier therefor, Fig. 3 is a top plan view of a valve; Fig. 4 is a side elevation of an adapter element; Fig. 5 is a plan view of the adapter element; Fig. 6 is a side elevation of the blade holder with blades mounted therein; Fig. 7 is a bottom plan view of the holder shown in Fig. 6; Fig. 8 is a section taken on the line 8—8 of Fig. 7; Fig. 9 is a section taken on the line 9—9 of Fig. 7; and Fig. 10 is a view in elevation of one of the cutting blades enlarged.

Similar numerals of reference indicate like parts throughout the several views on the drawings.

Referring to the drawings in detail, the numeral 1 indicates a fragment of a suitable type of internal combustion engine

cylinder provided with a valve seat 2 adapted to coact with the poppet valve 3, as is well known in the art, the valve being provided with the usual valve stem 4 slidably mounted in the guide bore 5. The engine cylinder is provided with an opening 6 which is threaded to receive a screw plug—not shown—to close the cylinder above the valve, as is well known in the art, through which opening my improved tool may be inserted for refacing the seat 2.

The numeral 7 indicates the blade holder consisting of a hollow cone-like element comprising the rim 8, the hub 9 and the web 10 connecting said rim and hub. The holder hub 9 may be vertically bored at 11 to receive the valve stem 4, and the holder web 10 may have a plurality or series of openings 12, 12 arranged around the hub 9, radially thereof, each of which openings may terminate at its bottom end at a socket 13 formed in the holder hub 9, said socket being arranged axially of a bore or chamber 14 (Fig. 1) formed in the holder rim 8.

The numerals 15, 15 indicate a plurality of cutting blades carried by the holder 7 and inclined to the axis thereof, the lower end of each blade being removably arranged in the socket 13, and its upper end removably arranged within the bore 14, each of which blades may be secured in the holder by a taper pin 16 removably mounted in the holder rim and penetrating one of the two blade shank apertures 17 formed therein at right angles and in the same plane. Each blade 15 may be provided with a plurality of sets of cutting edges 18, 18 and 19, 19, respectively, which are adapted for arrangement in the opening 12 in the holder web, said blade edges, when thus operatively positioned, extending through and beyond said opening and on both sides thereof, to enable the use of either of the blade cutting edges. When one set of the cutting edges of the blade 15, for example edges 18, 18, become dulled by use, the other set of cutting edges may be brought into operative position by rotation of the blade through ninety degrees, for which purpose the socket 13 and the bore 14 may be cylindrically formed.

The outer end of each blade 15 may be

transversely slotted at 20 to enable engagement by a screw driver, or other suitable tool, to effect rotation of the blade in its mount after disengagement of the pin 16 5 therefrom.

The top surface of the valve 3 is usually provided with a plurality of recesses 21, 21 to receive a spanner wrench for rotating the valve for grinding same in when pitted, as 10 is well known. Some valves have a transverse slot 22 formed therein to serve the same purpose, which also is well known. In practice, the valve stem 4 is thrust through the holder hub bore 11 and the face of the 15 valve brought into contact with the upper cutting edges of the blades, whereby the valve face may be resurfaced by rotation of the valve in any manner. When the valve seat 2 in the engine cylinder is to be resur- 20 faced the lower set of cutting edges of the blades 15 are brought into engagement therewith and rotation of the holder 7 ef- fected in any manner.

My improved reamer may be mounted in 25 a frame 23 consisting of the three legs 24, 25 and 26, effecting a T-shaped structure in top plan view, each of which legs has an angular prong 27 adapted to engage beneath the rim 8 of the holder 7 for clamping said 30 frame to the holder 7 by a clamping screw 28 threaded through said frame 23, the point of which screw is adapted to engage the ratchet wrench 29, the latter being seated upon the valve 3. The wrench 29 may have 35 lugs 30, 30 adapted to engage in the valve recesses 21, 21, and a handle 31, which wrench may be any suitable type of ratchet wrench. In the event the valve 3 is provided with the slot 22, I provide an adapter 40 element or plate 32 which is provided with the recesses 33, 33, adapted to receive the wrench lugs 30, said plate being provided also with a tongue 34 adapted to engage the 45 valve slot 22, for effecting rotation of the valve.

The point of the clamping screw 28 may engage in a recess 35 formed in the upper face of the wrench 29 to prevent displacement of the frame 23 and to maintain said 50 frame in position on the holder 7 and said wrench.

The adjustment of the clamping screw 28 may be regulated in relation to its engagement with the wrench 29, but ordinarily the 55 adjustment is loose enough to permit the rotation of the valve 3 against the cutting edges of the blades 15 by operation of said wrench. But a tighter adjustment of the screw 28 will set the valve 3 rigidly against 60 the blades 15, whereby, when the wrench 29, the valve 3 and holder 7 are assembled, as in Fig. 1, operation of the wrench will effect rotation of the holder 7 and the valve 3 in unison, thereby resurfacing the engine valve 65 seat 2.

I claim:

1. A tool of the character described consisting of a hollow conical blade holder comprising a hub, a rim and a web connecting the rim and hub, said web being provided 70 with a plurality of openings extending therearound, and said hub being bored to receive the valve stem of a valve; and a blade rigidly mounted in each of said holder web openings, said blade having oppositely 75 disposed cutting edges which are adapted to cut a valve face when a valve is arranged within the holder or a valve seat in an engine cylinder with the opposite blade cutting edge. 80

2. A tool of the character described consisting of a hollow blade holder provided with a centrally bored section and a plurality of radially extending blade openings arranged around said bored section, the bore 85 of said bored section being adapted to receive and sustain the valve stem of a valve, a cutting blade rigidly mounted in each of said blade openings and inclined to the axis 90 of said holder bore, one of said blades having a cutting edge adapted to engage and dress a valve face when the valve is arranged within said holder and the stem thereof is arranged within said holder bore, and another blade having a cutting edge adapted 95 to engage and dress a valve seat in an engine cylinder.

3. A tool of the character described consisting of a hollow conical blade holder adapted for rotation and provided with a 100 central integral hub section, such hub being provided with a plurality of blade sockets arranged therearound; and a circular series of blades rigidly mounted in said holder, adjustable therein and inclined to the axis 105 thereof, the lower ends of said blades being carried in said hub blade sockets.

4. A tool of the character described consisting of a hollow conical blade holder comprising a hub, a rim and a web connecting 110 the rim and hub, said web being provided with a plurality of openings extending therearound, and said hub being bored to receive a valve stem; a blade mounted in each of said holder openings, said blade being 115 provided with a plurality of cutting edges, of which blade cutting edges one is adapted to be disposed in an inoperative position when the other is operatively positioned; and means to enable movement of said blade 120 to bring any one of the blade cutting edges into operative position.

5. A device of the character described consisting of a hollow cone shaped holder element adapted to be arranged in a valve seat of 125 an internal combustion engine and to contain a valve therein, said holder element having a hub at its apex which is bored to receive the stem of said valve; a plurality of cutting blades removably mounted in said 130

holder in a series around the hub thereof, each of said blades being provided with oppositely disposed cutting edges; ratchet means for rotating the valve to resurface the face thereof; and clamping means associated with the ratchet means to effect simultaneous rotation of the holder and valve for resurfacing the valve seat in the engine cylinder.

In testimony whereof I have hereunto affixed my signature this 1st day of Aug., 1921.

FRED J. PALMER.
